UNITED STATES PATENT OFFICE.

WILLIAM J. KENT, OF NEW YORK, N. Y., ASSIGNOR TO ROSCOE R. BELL AND
ELIZABETH KENT, OF SAME PLACE.

DESIGN FOR A HOOF-PAD.

SPECIFICATION forming part of Design No. 31,642, dated October 10, 1899.

Application filed August 18, 1899. Serial No. 727,707. Term of patent 14 years.

To all whom it may concern:

Be it known that I, WILLIAM J. KENT, a citizen of the United States, residing in the city of New York, borough of Brooklyn, county of Kings, and State of New York, have invented or produced a certain new and original Design for Hoof-Pads, of which the following is a specification.

This design relates to hoof-pads for horses and to articles of this character which are attached to the hoof of the horse by being interposed between the sole of the hoof and the top bearing-face of the horseshoe. Such pads are usually adapted for a three-quarter shoe—that is, a shoe having short heels—the pad having a heel portion crossing the heel ends of the shoe, a bearing portion between the shoe and the sole of the hoof, and a frog portion within the shoe under the frog and the coffin-joint of the sole of the hoof.

The new design relates to the shape and the surface ornamentation of the hoof-pad.

This design is shown in the accompanying drawings, in which—

Figure 1 is an obverse or bottom face view of a hoof-pad embodying the new design. Fig. 2 is a reverse or top face view thereof. Fig. 3 is a side edge view thereof. Fig. 4 is a rear edge view thereof. Fig. 5 is a cross-section thereof, cut on the line 5 5 in Fig. 2; and Fig. 6 is a longitudinal section thereof, cut on the line 6 6 in Fig. 1.

Referring to the drawings, let A indicate the obverse face, B the reverse face, C the rear end, D the front end, and E the thin portion, of a hoof-pad, and F its edge.

A distinctive feature of my design as it relates to the shape of the pad is that the bottom or obverse side of the pad has a convex protuberance G projecting outwardly and

downwardly below the bottom face II of the heel C, which protuberance is approximately arc-shaped in both its cross-sections and is greatest in projection at its center, merging at its end into the face II of the heel and rising at its front and sides to the bearing E, with a gradual inclination at the front at a and a more acute inclination at the sides at b. The bottom face II of the heel is flat and of less projection than the protuberance G, and at each side of the latter the heel has upwardly-extending walls c, shown as inclined forwardly and rising to the bearing E. Another distinctive feature is that the reverse or top face of the pad has a central concavity I, which is disposed opposite the protuberance G, and consists of a recess below the top face J of the reverse side of the pad. The protuberance has a roughened or serrated surface, shown as composed of a plurality of longitudinally-extending projections d and intermediate depressions e, and the bottom face II of the heel C has roughening points or projections f and recesses g. The reverse face has a transverse bar or rib h, crossing the cavity I.

The new design is of distinctive shape, and its surface ornamentation produces a pleasing effect.

What I claim is—

The design for a hoof-pad substantially as herein shown and described.

In witness whereof I have hereunto signed my name in the presence of two subscribing witnesses.

WILLIAM J. KENT.
